[57] CLAIM

The ornamental design for a baseball trophy, as shown
and described.

DESCRIPTION

FIG. 1 is a front elevational view of a baseball trophy
showing my new design;

FIG. 2 is a right side elevational view thereof;

FIG. 3 is a top plan view of the figure alone with the
square base removed and the figure rotated approxi-
mately 45° clockwise; and

FIG. 4 is a bottom plan view thereof.

FIG. 1

FIG. 2

FIG. 3

FIG. 4
